BENDING MACHINE

Orville R. Owens, Chicago, Ill.

Application April 29, 1937, Serial No. 139,764

6 Claims. (Cl. 144—256)

The present invention is concerned with apparatus adapted to bend material such as wood and plywood in the production of trim, cabinets, etc. It is advantageous in the respects of its simplicity, 5 its ease of operation, its compactness, and its effectiveness in performance. The present improvements are directed to various of its features of construction as will be hereinafter pointed out in detail.

10 In the accompanying drawings, I have illustrated an exemplification of the present machine in the manner following:

Figure 1 is a perspective view of the machine in its entirety;

15 Fig. 2 is a perspective view of the work after bending has been performed;

Fig. 3 is a transverse section taken on line 3—3 of Fig. 1;

20 Fig. 4 is a similar view showing the dies advanced into work engaging position;

Fig. 5 is a fragmentary vertical section of one end of the male die, showing the support therefor;

Fig. 6 is a view in perspective of the heater elements which may be associated with the male 25 die;

Fig. 7 which is a view similar to Fig. 3 shows a modified construction of the female die for forming a bend of more than 90°;

Fig. 8 which is a similar view shows a further 30 modified form of die for bending material over the rounded edge of a block;

Fig. 9 which is a similar view shows a die for bending material in conformity with an arched base; and

35 Fig. 10 is a vertical section through a bending machine which is modified for duplex operation.

The present apparatus may comprise a base B from which rises a pair of spaced supports 15 forming guides upon which a head H is slidingly 40 mounted. The head is supported by multiple rods 16 each entering one end of a vertical cylinder 17 forming part of a piston mechanism adapted to be operated by fluid under pressure. These cylinders which are mounted on the base are 45 interconnected by a pipe 18 with an interposed T-fitting 19 with which is connected a pipe 20 leading to a two-way throttle valve 21 having a pedal control 22. From this same valve is extended a second pipe 23 leading to a T-fitting 24 50 which is interposed in a second pipe 25 interconnecting the several cylinders here shown as two in number. By operation of the valve fluid pressure is simultaneously admitted into or released from the two cylinders whereby their rods are raised 55 or lowered in unison to operate the head. Lead-

ing from the control valve is a pipe 26, with an interposed speed regulating valve 27, connecting with a suitable fluid pressure source (not shown).

Mounted upon the head is a block 30 which supports a female die 31 wherein is fitted a caul 32. 5 Adjacent this die is a rack 35 hinged thereto as at 36 adapted to swing upwardly from a horizontal position to support thereon the work W which is to be operated upon. The rack is provided with a rail 37 fitting into and against a stop 38 in the 10 die whereby to support the rack normally in a horizontal position. A stop 39 is also carried by the rack against which the work may be rested for accurate positioning over the die.

Mounted at the top of each support is a chambered fitting 40 having a circular opening facing the opposite fitting. Each opening may be internally threaded to receive a mounting ring 41 whose inner surface, as shown, is also threaded to receive engagement from one end of a cylindrical 20 tube 42 forming the male die which is complementary to the die 31. This tube which is open from end to end accommodates within itself a heating element which may be of the kind shown in Fig. 6, comprising two spaced insulating disks 25 45 supporting therebetween a pair of bars 46 in angular relation, each bar carrying a resistance element so that when connected to a source of electrical energy ample heat will be given off to raise the temperature of the male die. The two 30 bars are located relatively close to the lower portion of this die where engagement is made with the work, and in consequence the heat which is required in the bending operation is delivered at the point where most needed. As shown best in 35 Fig. 1, a lead 47 extends to a switch box 48 on the outside of one fitting 40, and thence into the male die to connect with the heating elements to supply electrical energy thereto.

The description up to this point has particular 40 reference to the construction illustrated in Figs. 1—6 inclusive. In operation, pressure is first released from the two cylinders permitting the head to descend. The work to be bent is then positioned in the clearance between the male and 45 female dies (see Fig. 3), the treadle valve is then actuated to admit fluid to the cylinders, and the head H is thereupon advanced upwardly. In this movement the caul-faced female die is pressed against the underside of the work which, in consequence, is bent around the male die as a form 50 to a final position which is about as represented in Fig. 4. While undergoing this movement the attendant may manually push the rack so as to aid in uplifting the extended portion of the work 55

which is not subjected to pressure. It will be noted that the work is engaged on the one side by the male die and on the other by the caul which is seated in the female die. It is bent to its final shape while undergoing both heat and pressure which is continued for a brief interval sufficient to assure permanency to the bend. It is desirable that the regulating valve 27 be so adjusted that the operating stroke of the cylinder mechanisms may be perfectly controlled as to speed, otherwise the work may be subjected to an impact which will be detrimental to the bend which is desired.

As shown in Fig. 4, the co-operating dies will produce in one operation a bend of approximately 90°. The same dies may be employed to produce a bend of substantially 180° in two operations. A different set of dies, as suggested in Fig. 7, will produce a bend of around 180° in one operation. This is accomplished with a male die 52, the same as already described, in co-operation with a female die of two parts 51^a and 51^b hinged together so as to swing apart, as shown by dotted lines. The die part 51^b is supported on the head H so as to advance upwardly therewith; the die part 51^a on the other hand is carried by the other die part, and tends to swing away therefrom to rest against the head H except when engaged by a cam surface 53 which is encountered in its movement toward the male die. At the completion of this movement the two die parts 51^a and 51^b are completely closed so that the space therebetween defines a concave form having a continuous circular contour of about 180°. Initially the work is rested upon the female die part 51^b, as shown by dotted lines, but in response to pressure resulting from engagement with the male die, the work is bent and shifted around to its final position, concurrently with closing of the female die part 51^a, all as indicated by full lines in Fig. 7.

Another example of bending that may be advantageously performed with the present device is indicated in Fig. 8 where I have shown upon the head H a block 55 of wood or the like having a convex rounded edge 56. The work W is placed over the block, with an intervening layer of glue, if desired, to receive pressure from a die 57 against which the work is upwardly advanced in response to movement of the head H. The die, as shown, is concavely rounded off at 58 in conformity with the curved edge of the board so as to bend the work therearound and press the same tightly thereagainst.

A further example of use to which the present machine may be put is suggested in Fig. 9 where I have shown the head H as supporting a die block 60 having a bowed contour 61 furnishing a seat for a board 62 which is bowed, or to be bowed, in conformity therewith. The work W may be in the form of a thin strip which is to be applied to the convex surface of the board. For this purpose the die 63 like the die 57, in Fig. 8, may be heated by suitable heating means common in the art, is provided with a concave surface against which the strip is seated in response to upward movement of the head H which carries with it the block 62, heat and pressure being maintained as long as desired. The strip is caused to adhere to the board and, when removed from the machine, will remain inseparably united thereto.

Each of the mechanisms described is adapted to perform a bending operation upon a single piece of work. By employing a duplex apparatus

as suggested in Fig. 10, two or more bending operations, each upon a separate work, may be performed simultaneously. This is accomplished by utilizing multiple cylinders 17 connected with a movable head H whereon is supported a female die 65 adapted to co-operate with a male die 66 thereabove. In this case, however, the male die is suspended from an upper head H' over which is affixed a female die 67 adapted to co-operate with an upper male die 68 therefor having a fixed mounting between spaced supports one of which is shown at 69. Suitable stops 70 are provided for sustaining the upper head H' with its associated female die 67 and male die 66 at a point of minimum elevation which is sufficient to maintain a clearance between this male die and the female die 65 therebelow when pressure is released from the cylinder mechanism. A similar clearance is preserved between the upper female die 67 and the co-operating male die 68 thereabove when the upper head H' is sustained by the stops 70 at a point of minimum elevation. Upon the racks 71 I may position separate pieces of work W each adapted to be engaged by the proximate pair of dies in response to upward movement of the lower head H which transmits movement through the dies thereabove to the upper head H', which in turn advances the upper female die 67 against the top male die 68 whose position is fixed. The result is a simultaneous bending operation performed upon each piece of work that is positioned between the co-operating dies. It will be found that this duplex type of machine has advantages for certain work, in that it increases the output for a given unit of time.

The present mechanism is advantageous in that it is simple, inexpensive, compact, and easily operated. Removal of the dies and substitution of others may be readily accomplished whenever desired. If the male die is to be of different diameter, then a new mounting ring of appropriate size will be used.

I claim:

1. In a bending machine the combination of a base, supports extended upwardly from the base, a head slidably mounted on the supports, a die member fixedly mounted upon the supports above the head, a co-operating die member rigidly carried by the head and movable therewith toward and from the fixed die member, means for heating one die member, said cooperating die member including a relatively movable work supporting rack hingedly mounted on one side thereof so as to form a continuation of said co-operating die when following bending movement of work which is positioned between the die members, and fluid-operated cylinder mechanism mounted on the base in connection with the head adapted to raise and lower the latter.

2. In a bending machine the combination of a base, supporting means extended upwardly from the base, a head slidably mounted on the supporting means adapted for vertical movement thereupon, a die above the head mounted fixedly upon the supporting means, a second die cooperating therewith carried by the head, means for heating one of the dies, and means laterally associated with the second die for supporting and engaging the work which is positioned between the two dies and adapted to follow the movement of the work during bending under pressures exerted thereon by the dies.

3. In a bending machine the combination of a base, supports extended upwardly from the base,

5 a fixed die member extended between the supports, a co-operating die member rigidly carried by the supports and slidable therewith toward and from the fixed die member, another pair 10 of co-operating die members below those just named each having a sliding mounting between the supports, relatively movable members hinged to each slidably movable die for positioning work between each pair of co-operating dies, said 15 relatively movable members being swingable relative to its movable die member so as to form a continuation of the working face thereof and pressure mechanism extended between the base and the lowermost die adapted to advance the latter upwardly whereby to produce a pressure 20 between each pair of co-operating dies and the work therebetween.

4. In a bending machine the combination of a base, supports extended upwardly therefrom, 25 a die fixedly extended between the supports, a co-operating die movable toward and from the first die adapted for co-operation therewith to bend work which is positioned therebetween, the movable die comprising two parts one hinged to the other and free to swing relative thereto, a head slidably carried between the two supports and furnishing a mounting for one of the two parts of the movable die, means for raising and lowering the head whereby the movable die in 30 its entirety is advanced toward and from the

fixed die, and other means for forcing the free swinging die part toward the other as the head is advanced toward the fixed die.

5. In a bending machine the combination of a base, supporting guides extending vertically from said base, a fixed member having a lower die face extending horizontally between said guides, a member movable toward and from the fixed member on said guides and adapted to support and carry thereon the work to be bent over said lower die face, the movable member comprising two parts one a rigid die part fixed thereon and the other a work engaging part hinged to the fixed part for swinging movement relative thereto.

6. In a bending machine a pair of vertical guides, a fixed die member extending between said guides adjacent the upper ends thereof, a cooperating member slidably mounted on said guides for movement toward and from said fixed member, said last member comprising a rigid die part fixed thereto and a part hinged to one side of the rigid die part for relative vertical swinging movement whereby in one position of said relatively swinging part it will be caused to form a continuation of said rigid die part in co-operating therewith to support and embrace work raised by said cooperating member into engagement with said fixed die member.
